(57) **CLAIM**

The ornamental design for a luggage shell with surface configuration, as shown and described.

DESCRIPTION

FIG. 1 is a perspective view of the luggage shell with surface configuration in a first environment showing a representative luggage shell in broken lines;

FIG. 2 is a front view thereof;

FIG. 3 is a rear view thereof;

FIG. 4 is a right side view thereof;

FIG. 5 is a left side view thereof;

FIG. 6 is a perspective view of the luggage shell with surface configuration in a second environment showing a representative piece of luggage in broken lines;

FIG. 7 is a front view thereof;

FIG. 8 is a rear view thereof;

FIG. 9 is a right side view thereof; and,

FIG. 10 is a left side view thereof.

The broken lines showing luggage are for the purposes of illustrating environment and forms no part of the claimed design.
